US0D1109403S

(12) **United States Design Patent** (10) **Patent No.:** **US D1,109,403 S**
Wen (45) **Date of Patent:** **** Jan. 13, 2026**

(54) **MOTION SENSOR LAMP**

(71) Applicant: **Shenzhen TIZE Technology Co., Ltd,**
Shenzhen (CN)

(72) Inventor: **Jian Wen**, Shenzhen (CN)

(**) Term: **15 Years**

(21) Appl. No.: **29/947,256**

(22) Filed: **Jun. 13, 2024**

(51) **LOC (15) Cl.** **26-05**

(52) **U.S. Cl.**

USPC **D26/85**; D26/108; D26/89

(57) **CLAIM**

The ornamental design for a motion sensor lamp, as shown and described.

DESCRIPTION

FIG. 1 is a front perspective view of a motion sensor lamp, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view.

The broken lines in the drawings illustrate the portions of the motion sensor lamp, which form no part of the claimed design.

1 Claim, 8 Drawing Sheets
